INDUSTRIAL VACUUM CLEANING UNIT

Ira J. Alligood, Jr., 184 Scarboro Drive,
York, Pa. 17403

Filed Jan. 22, 1968; Ser. No. 10,240

Term of patent 14 years

Int. Cl. D15—06

U.S. Cl. D49—11

FIG. 1 is a perspective vertical front view of an industrial vacuum cleaning unit embodying my design.

FIG. 2 is a side perspective thereof.

FIG. 3 is a top plan view thereof as seen from line 3—3 of FIG. 1.

The essential features of the design reside in the portion shown in full lines.

I claim:

The ornamental design for an industrial vacuum cleaning unit, as shown and described.
